Primary Examiner — Kevin Rudzinski**CLAIM**

The ornamental design for a LED reflector, as shown.

DESCRIPTION

FIG. 1 is a top plan view of a LED reflector showing my new design;

FIG. 2 is a bottom plan view thereof;

FIG. 3 is a front elevational view thereof;

FIG. 4 is a back elevational view thereof;

FIG. 5 is a left side elevational view thereof;

FIG. 6 is a right side elevational view thereof; and,

FIG. 7 is a perspective view thereof.
